PATRICK KENNY, OF NEW YORK, N. Y.

Letters Patent No. 63,531, dated April 2, 1867.

IMPROVEMENT IN SHIRT STUDS.

The Schedule referred to in these Letters Patent and making part of the same.

TO ALL WHOM IT MAY CONCERN:

Be it known that I, PATRICK KENNY, of the city, county, and State of New York, have invented a new and useful Improvement in Shirt Studs; and I do hereby declare that the following is a full, clear, and exact description thereof, which will enable others skilled in the art to make and use the same, reference being had to the accompanying drawing, forming part of this specification, in which—

Figure 1 is a top view of the upper plate of my improved stud.

Figure 2 is a central cross-section of the same through the line *x x*, fig. 1.

Figure 3 is an under side view of the under plate.

Figure 4 is a central cross-section of the same through the line *w w*, fig. 3.

Figure 5 is a top view of my improved stud.

Figure 6 is a side view of the same.

Figure 7 is a central cross-section of the same through the line *y y*, fig. 5.

Figure 8 is a side view of one of the elastic bands by which the two plates are connected together.

Figure 9 is an edge view of the two bands and the pins by which the bands are connected to the plates.

Similar letters of reference indicate like parts.

My invention is designed to furnish a shirt stud by the use of which, from the elasticity of the connection between the plates, the button-holes in the shirt bosom will be less liable to be torn or injured, and which will be more easily inserted and removed than the studs now in common use with rigid connection. And it consists of a shirt stud the plates of which are connected together with an elastic connection, as hereinafter more fully described.

A is the upper and B the under plate of the stud. These may be made of any of the ordinary materials of which studs or buttons are now made, and of any of the ordinary forms. They should have holes through their centres, and these holes should be countersunk, that of the plate A from the upper side, and that of the plate B from the under side, as represented in the drawings. The connection between the plates is formed by rubber or other elastic rings or bands, C, one or more to each stud. I prefer to use two rings, but the number is not material. Through the ends of these rings C are passed short pins, D, as represented in fig. 9. These pins D should be of such a length as to reach across and pass into the enlarged part of the holes through the plates A and B and rest upon the shoulder formed in said plates, as shown in fig. 7. This forms the connection between the upper and lower plates. This method of securing the elastic connection I prefer, but the connection may be made in various other ways; the material point being that the two plates be attached to each other by an elastic connection. The stud may be completed and at the same time ornamented by inserting a stone or other ornament in the plates, as shown in figs. 5, 6, and 7. By this arrangement the button-hole is relieved from sustaining the full force of any sudden strain by the elasticity of the connection C.

I claim as new, and desire to secure by Letters Patent—

The perforated plates A and B, countersunk on opposite sides, forming shoulders in the centre of the plates, on which bear pins D, around which the connecting loops C pass, holding the plates together with an unbroken flexible connection, in the manner described for the purpose specified.

The above specification of my invention signed by me this 27th day of December, 1865.

PATRICK KENNY.
